UNITED STATES PATENT OFFICE.

JOHN ADAM KUSTER, OF PLYMOUTH, WISCONSIN.

ADJUSTABLE MOUNTING FOR SLIDING DOORS.

SPECIFICATION forming part of Letters Patent No. 595,180, dated December 7, 1897.

Application filed March 11, 1897. Serial No. 627,040. (No model.)

To all whom it may concern:

Be it known that I, JOHN ADAM KUSTER, a citizen of the United States, residing at Plymouth, in the county of Sheboygan and State 5 of Wisconsin, have invented certain new and useful Improvements in Adjustable Mountings for Sliding Doors; and I do hereby declare the following to be a full, clear, and exact description of the invention, such as 10 will enable others skilled in the art to which it appertains to make and use the same.

My invention, as will be hereinafter fully described and claimed and illustrated in the accompanying drawings, made a part of this 15 application, has reference to certain new and useful improvements in mechanism for mounting sliding doors for residences and all other kinds of buildings where such a door is desirable.

20 The object of my invention is to provide an adjustable track which will permit the door to freely travel from one end to the other thereof without obstruction or binding.

Another object of my invention is to render 25 it possible for any person, whether a skilled mechanic or not, to so adjust the track that compensation will be easily made for any settling of the partition or other walls of the building, thus preventing the door from becoming sagged at one side and the binding or 30 wedged condition incident thereto.

With the foregoing objects in view attention is called to the drawings, in which—

Figure 1 is a side elevation of my invention 35 as applied to the inner side of one row of studding. Fig. 2 is a vertical section thereof on line *a a*. Fig. 3 is a perspective view of the yoke. Fig. 4 is a detail of the retaining plate and hooks. Fig. 5 is a detail of adjusting-seat for threaded shaft.

Reference will be had to various details by figures, 1 indicating the inner surface of one row of studding, to the outer surface of which lath and plaster are secured in the usual 45 manner.

At a convenient point above the door I secure to one of the studding the plate 2, having attached thereto the journal 3, upon which is pivoted the lever 4. To the outer end of 50 the lever 4 I pivotally attach the supporting-shaft 5, designed to extend downward to the outer end of the track 6, to which it is adjustably secured by means of the nuts 7. To the inner end of the lever 4 I pivotally attach

the adjusting-loop 8, designed to receive the 55 threaded end of the shaft 9, the lower end of which terminates in the square adjusting-point 10, which extends entirely through the track. The other end of the track is adjustably supported by the threaded shaft 11, 60 formed substantially the same as shaft 9, the upper end thereof being seated in the threaded loop 12, formed substantially the same as loop 8. The shafts 9 and 11 are made with right and left screw-threads, so that 65 when a tool is applied to the square end 10 of either shaft the track may be easily and quickly raised or lowered. The square end 10 is always accessible, and this form of construction is more preferable than when the 70 rods 9 and 11 have the same hand-thread with nuts on the same just above and below the track for its adjustment. This latter form of construction is preferable for the right-hand screw-rod No. 5. This rod, carrying a nut 7, 75 passes loosely through the strap or angle iron 15 and takes in a threaded nut on the under side of the upper surface 6^a of the track. This end of the track is at the outset adjusted in position by manipulating the nut 7 and the 80 nut on the under side of the track. The supports 9 and 11 could be connected to the track in the same way and be adjusted in the same manner, but it is preferred to screw-thread 85 the straps 15 and dispense altogether with the nuts above and below the track. Both of these supports being just above the door or in the doorway can be easily reached and readily adjusted. It will be evident that the purpose of the lever 4 and attachments is 90 to permit the adjustment of the end of the track, supported by the rod 5, which is both out of sight and out of reach, through the right and left threaded rod 9. The other end of the track is adjusted by the right and left 95 screw-support 11. All these supports pass loosely through the top of the track, whereby sufficient play is allowed to avoid rigidity and any binding action of the parts. The straps 15 are pivoted to the side bars of the 100 track by screws, as shown, or by any other suitable means. Said loop 12 is pivotally attached at its upper end to the journal 13, rigidly secured and held in position by the retaining-plate 14, attached at a convenient 105 point to one of the studding. The track is provided at its point of connection with the several supporting-shafts thus described by

angle-irons 15, so formed that they will extend across the top of the track and upon each side thereof, where they are held by screws or other suitable means.

5 The track proper, 6, consists of the upper horizontal section 6^a and the downwardly-extending members 6^b, each of the latter being provided upon the inner surface of its lower edges with the rails 6^c, designed to receive the tread of the wheel 16.

As will be seen in Fig. 1, I prefer to provide a pair of wheels for each side of the door or for each part thereof which it may be deemed necessary to support. Said wheels 15 16 are connected rigidly to an axle 17 of sufficient length to permit each wheel to rest upon its own track. If deemed necessary, the wheels may be provided with flanges to more reliably guide the movement, while the upper surface of the rails may be reinforced by strap-iron or otherwise. Designed to extend from the axle to the door I mount between the wheels the yoke 18, formed of cold-rolled steel or other preferred material and having 20 the horizontal upper section 19, the depending sections 20 extending at right angles therefrom and the curved terminal sections 21.

25 The yoke 18 is made in the form shown, a space being left between the terminal sections 21 in order that it and the supporting-wheels may be easily removed and replaced in refitting or repairing the supporting devices of the door.

30 The sections 20, it will be understood, extend sufficiently far to properly receive or form connection with the hooks 22, integrally formed with the plate 23, or otherwise attached thereto. The said plate is designed to be attached directly to the upper edge of the door 40 after the same has been properly trimmed ready for assuming its operative position by means of the retaining-screws 24, as shown.

35 The object in providing a hook which shall be rigidly attached to the door is to enable the door to be readily disengaged from the supporting-yoke when it may be necessary to gain access to the track or other parts.

40 The operation of my invention may be stated to be as follows—that is to say, the track is adjustably suspended in position over the opening forming the proposed door. This location of the track is preferably done during the process of constructing the walls. The several pairs of wheels are mounted upon 55 the track and provided with an individual yoke, the ends of which extend slightly below the track proper, but not far enough to protrude beyond the line of the proposed finish. After these parts have thus been assembled the track may be so adjusted that it will occupy a true horizontal plane, which adjustment is effected by a suitable wrench adapted to act upon the square ends of the threaded shafts. If, for instance, the outer 60 end of the lever 4 should hold its end of the track higher than the other end, a true adjustment may be readily effected by properly ro-

tating the threaded shafts 9 and 11, the same action being taken should said lever hold its end of the track lower than the opposite end. 70 After the track has thus been truly adjusted the doors, when trimmed in the usual manner, are ready to be hung in position after first having secured thereto in the manner stated the retaining-plate 23. The hooks 22 75 are then caused to engage the terminal sections or hooks 21. The complete finish may then be added. If at any time thereafter it is found that the track needs readjustment to compensate for an uneven settlement of the partitions, the doors may be readily unhooked from the yoke, as it will be understood that the line of finish shall not prevent the door being moved laterally sufficiently to effect such disengagement. 85

Believing that the advantages, construction, and operation of my invention will be made fully apparent by the foregoing specification and the accompanying drawings further description is deemed unnecessary. 90

Having thus described my invention, what I claim as new, and desire to secure by Letters Patent, is—

1. In a sliding door, a track for the same, pivoted, screw-threaded loops, and threaded bolts connecting the loops and the track for adjusting the track, as set forth. 95
2. In a sliding door, a track for the door, pivoted loops, and adjusting devices connected directly to the loops and attached to the track, as set forth. 100
3. In sliding doors, a track for the same, adjustable supports at each end of the track, one of the supports consisting of a pivoted lever having a loop carrying a screw-bolt pivoted thereto at one end, and a pivoted screw-bolt at the other end, as set forth. 105
4. In sliding doors, a track provided with pivoted loop-supports and rollers, said supports including a pivoted lever carrying adjusting devices at each end thereof attached to the track, as set forth. 110
5. In sliding doors, a track adjustably supported at each end, one of said supports consisting of a pivoted lever carrying a pivoted screw-bolt at one end and a pivoted loop at the other end carrying a screw-bolt, and devices connecting said screw-bolts to the track, as set forth. 115

6. In sliding doors, a track, pivoted loops carrying adjusting devices connected to the track, as set forth. 120

7. In sliding doors, a track having screw-threaded attachments, pivoted supports consisting in part of screw-threaded links, and screw-bolts connecting the links and the track, all combined as set forth. 125

In testimony whereof I affix my signature in presence of two witnesses.

JOHN ADAM KUSTER.
